WORK HOLDING FIXTURE

Elwin M. Strickland, Detroit, Mich., assignor of
one-half to Albert F. Wall, Grosse Pointe,
Mich.

Application November 24, 1943, Serial No. 511,590

7 Claims. (Cl. 51—97)

1

This invention relates to a work holding fixture and more particularly to a fixture for generating true spherical shapes or contours.

In certain mechanical devices ball and socket joints are used in link connections to transmit motion from one member to another. Considerable difficulty has been experienced because of the virtual impossibility of forming accurate matching surfaces between the ball and socket members. These difficulties arise from the fact that in forming the surface of the ball or the socket the cutting edge of the tool must be maintained accurately in alignment with the center line of the axis of the rotating member, and the vertical axis of the pivot must be maintained accurately at right angles to the horizontal axis of the rotating member to prevent the formation of an elliptical contour.

The cutting and polishing tools heretofore employed operate at right angles to the rotating axis of the spindle or other ball or socket carrying member. Tool marks or ridges are thus formed on the surface of the ball or socket, and since the tool marks all run in the same direction it is virtually impossible to remove them. These marks may be reduced somewhat by polishing, but since the polishing marks also extend in the same direction, the difficulties are not eliminated but merely reduced somewhat. These concentrically extending tool marks cut through the oil film employed to lubricate the joint and cause binding and galling of the surfaces of the ball and seat members.

I have found that these difficulties can be overcome only by operating the cutting tools and polishing members at different and preferably constantly changing angles to the surface of the ball or socket members as the grinding or polishing operations progress to provide smooth spherical surfaces free from tool marks.

An object of this invention is therefore to provide a work holding fixture for generating true spherical shapes.

A further object of the invention resides in the provision of a work holding fixture for generating true spherical shapes, wherein the cutting or polishing tool and the work revolve relative to each other and simultaneously oscillate in two intersecting planes to prevent the formation of tool marks in a single direction on the work.

Another object is to provide an improved ball or socket forming machine having a work holder mounted for rotation relative to a cutting or polishing tool, and wherein the work holder is mounted for oscillation about intersecting vertical and horizontal axes.

Yet a further object resides in the provision of flexible driving members for simultaneously rotating a ball or socket member relative to a cutting or polishing member and simultaneously

2

oscillating the ball or socket member about intersecting oppositely disposed axes.

Still another object of the invention is to provide an economical method of accurately forming spherical ball and socket members free from tool marks.

A further object resides in the provision of an improved holder for maintaining a ball in an accurate position relative to a cutting or polishing member.

Other objects and advantages of this invention will be apparent from the following detailed description considered in connection with the accompanying drawings, submitted for purposes of illustration only and not intended to define the scope of the invention, reference being had for that purpose to the subjoined claims.

In the drawings wherein similar reference characters refer to similar parts throughout the several views:

Fig. 1 is a plan view of a work holding fixture embodying the present invention.

Fig. 2 is a side elevation of the device illustrated in Fig. 1.

Fig. 3 is a sectional view taken substantially on the staggered line 3—3 of Fig. 2 looking in the direction of the arrows.

Fig. 4 is a sectional view of a cutting tool holder.

Fig. 5 is an end elevation, partly in section, taken substantially on the line 5—5 of Fig. 4 looking in the direction of the arrows.

Fig. 6 is a fragmentary side elevational view of a modified form of a cutting element.

Fig. 7 is a view similar to Fig. 6 showing a still further modified form.

Fig. 8 is a fragmentary sectional view illustrating the application of the invention to the formation of spherical sockets.

Fig. 9 is a fragmentary sectional view illustrating an improved method of holding a ball during the forming or polishing operations.

Fig. 10 is a plan view of a modified form of the invention.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Referring now to the embodiment of the invention illustrated in Figs. 1 to 5 it will be noted that a work carrying table or base 10 is mounted on a support 12 by means of transverse and longitudinally extending ways 14 and 16 respectively whereby the work table 10 may be moved transversely or longitudinally relative to a cutter

carrying member 18 mounted on a suitable support.

A vertically extending yoke 20 having spaced arms 22 carried by a shaft 24 is journaled in the table 10 and is mounted in spaced oppositely disposed bearings 26 and 28 positioned in the plate 10 and in a housing 30 secured to and projecting beneath the table 10. The shaft 24 is provided with a ring gear or worm 32 meshing with a worm gear 34 journaled in the housing 30. The worm gear 34 may be driven by a flexible shaft 36 to rotate the shaft 32 and spaced arms 22 of the yoke 20 about a vertical axis. Suitable reversing mechanism may be provided to oscillate the arms 22 back and forth over a desired predetermined arc. One suitable reversing mechanism comprises a bearing block 69 supporting one end of the shaft 68. The shaft 68 is provided with a hand wheel 71 adapted to be actuated by a lever 73.

A work carrying spindle 38 is mounted in a yoke 40 having spaced arms 42 journaled on stub shafts 43 carried by the arm 22 for oscillation about the horizontal axis defined by the upper ends of the arms 22 of the yoke 20. The work carrying spindle 38 comprises a chuck 44 adapted to engage and hold the projecting arm 46 of a ball 48 to accurately hold the ball in a predetermined position with the center of the ball positioned at the intersecting axes of the arms 22 and 42 of the yokes 20 and 40 respectively.

The chuck 44 is provided with an extended shaft 50 having a ring or pinion gear 52 positioned in a housing 54 clamped to a cylindrical barrel 56 surrounding the shaft 50. A worm gear 58 driven by a flexible shaft 60 is journaled in the housing 54 to engage and rotate the pinion gear 52 to rotate the ball 48 about the intersecting axes of the arms 22 and 42 respectively.

One of the stub shafts 43 is provided with a ring gear or worm gear 62 positioned in a housing 64 and meshing with a worm gear 66 driven by a flexible shaft 68 and a suitable reversing mechanism such as a wheel 39 having an actuating member 41 secured to the shaft 36 journaled in a suitable bearing 31 to oscillate the work holder 38 and yoke 40 about the horizontal axis of the arms 22 of the vertically positioned yoke 20.

A suitable source of power such for example as an electric motor 70 is carried by the plate 10 and is provided with a shaft 72 adapted to drive the flexible shafts 36, 60 and 68 to rotate the ball 48 about the longitudinal axis of the holder 38 and to simultaneously oscillate the ball about the vertically and horizontally intersecting axes of the yokes 20 and 40.

The cutter carrying member 18 may be provided with a driven shank 74 having a body portion 76 supporting spaced cutting or polishing members 78 as more clearly illustrated in Figs. 4 and 5. The cutter members 78 may be yieldingly urged into engagement with the surface of the work by means of calibrated springs 79 controlled by manually operable screws 81.

The operation of this embodiment of the invention is as follows. The projecting arm 46 of the ball 48 is positioned in the work engaging chuck 44 with the center of the ball in alignment with intersecting axes of the arms of the yokes 20 and 40 respectively.

The transversely and longitudinally extending ways 14 and 16 are actuated to align the surface of the ball 48 in a desired cutting relation with reference to the rotating cutting elements

78 carried by the projecting arm 14 of the cutter carrying member 18. The motor 70 is then operated to drive the flexible shafts 36, 60 and 68. The flexible shaft 60 drives through the worm and worm gears 58 and 52 respectively to rotate the ball 48 about the axis of the cylindrical barrel 56. The surface of the ball 48 is engaged by the rotating cutting elements 78 to grind the surface of the ball.

Simultaneously with the rotation of the ball relative to the cutting or polishing elements the ball is oscillated about the intersecting vertical and horizontal axes. The worm and worm gears 32 and 34 oscillate the yoke 20 about the vertical axis, and the worm and worm gears 62 and 66 oscillate the yoke 40 about the horizontal axis of the yoke 20.

The cutting elements thus are constantly moved relative to the surface of the ball 48 and do not form concentric tool or polishing marks on the surface of the work in a single direction as is customary in ball or socket grinding machines heretofore employed.

It will be understood that if desired a polishing member may be substituted for the cutting element 78 in the embodiment illustrated in Figs. 4 and 5. It will also be apparent that other types of cutting or polishing members may be substituted for the cluster of cutting elements illustrated in Figs. 4 and 5.

Suitable reduction gearing may be employed to control the rates of oscillation of the ball 48 about the intersecting vertical and horizontal axes as the ball rotates to maintain a desired relationship between the oscillating and rotating movements.

Fig. 6 illustrates a different type of cutting element wherein a substantially flat plate 80 having angularly related cutting teeth 82 is carried by the projecting arm 14 of the tool holder to engage the surface of the ball 48.

If desired a cutting or polishing member may be carried by the chuck 44 to rotate and oscillate in the manner discussed above, and the ball or socket member to be carried by the member 18. If this expedient is resorted to, it will be apparent that the center of the ball or the socket should be positioned at the intersection of the arms 22 and 42 of the yokes 20 and 40 respectively.

Fig. 7 illustrates an embodiment of the invention wherein a different type cutting or buffing tool 84 is carried by a rotating shaft 86 projecting from the cutter carrying member 18.

Fig. 8 illustrates the application of the invention to the formation of a socket 88. An arm 90 carried by a member 92 having a socket 88 therein may be positioned in the holding chuck 44. A cutting tool 96 on a shaft 98 carried by the tool carrying member 18 may project into socket 94 to finish the surface thereof. As suggested above both members may be rotated in opposite directions while one member oscillates in the opposite planes discussed above to effect the desired finish of the surface of the socket 94.

Fig. 9 illustrates the application of the invention to a ball 100. The ball may be positioned in the resilient holding end portion 102 of a support 104. The portion 102 may be formed of rubber and the portion 104 of metal. The holder 104 may be secured in the holding chuck 44 of the work carrying member as illustrated in Figs. 1 to 3. The holder 104 may be hollow as illustrated at 106 to subject the surface of the ball to vacuum to hold it in a predetermined position as illustrated. When one side of the ball has

been contoured as desired, the vacuum may be released and the ball moved to expose a different surface for contact with the cutting or polishing members.

The embodiment of the invention illustrated in Fig. 10 is similar in many respects to that illustrated in Figs. 1 to 3. Corresponding parts have therefore been given corresponding reference numerals with the addition of 100.

It will be noted that the yoke 120 has a single arm 122, and that the yoke 140 has a single arm 142 journaled on the stub shaft 143. A hand wheel 165 is provided to actuate the chuck 144 to clamp the shank 146 of the ball 148 in the rotatable shank 150.

A one-way brake 167 interposed between the rotating shank 150 and a non-rotating member 169 is provided to hold the rotatable shank 150 and ball 148 from rotating with a high speed cutting or buffing wheel 171 fixed to a rotating shaft 173. A hand wheel 175 is provided to actuate the one-way brake 167 through suitable gearing and rotate the shank 150 and ball 148 against the cutting or buffing wheel 171 to expose a different surface of the ball to the wheel.

The operation of this embodiment of the invention is as follows: The shank 146 of the ball 148 is clamped in the chuck 144 by actuation of the hand wheel 165 to position the center of the ball 148 at the intersection of the axes of the arms 122 and 142 of the partial yokes 120 and 140. The surface of the ball is then moved into contact with the surface of the cutting or buffing wheel 171 by actuation of the ways on which the table 110 is supported, and the wheel 171 is rotated.

The ball 148 is oscillated about the intersecting vertical and horizontal axes of the partial yokes 120 and 140 by movement of the yoke 140, and the ball 148 is rotated against the wheel 171 by operation of the hand wheel 175 to expose fresh surfaces of the ball 148 to the wheel 171 and to prevent the formation of tool marks in a single direction.

In this embodiment the ball 148 is actuated manually about the intersecting horizontal and vertical axes and is rotated on the axis of the shank 146 as the surface of the ball is contacted by the finishing wheel 171. The formation of tool marks in a single direction on the surface of the ball is thus prevented and an accurate and smooth surface free from tool marks may readily be formed.

It will be apparent that this embodiment may be employed in the formation of sockets as illustrated in Fig. 8 or complete balls as illustrated in Fig. 9.

I claim:

1. A work holding fixture for forming spherical surfaces comprising two yokes having spaced arms, connecting means between said arms, means to oscillate one of the yokes about its longitudinal axis, means to oscillate the other yoke about the intersection of said arms, a work holder carried by one of the yokes to position a piece of work at the intersection of the yokes, and a finishing tool positioned to engage the work.

2. A work holding fixture for forming spherical surfaces comprising a base, a first yoke journaled in the base, means to oscillate said yoke about its longitudinal axis, a second yoke journaled in the first mentioned yoke, means to oscillate the

second yoke about the transverse axis of the first yoke, a work holding chuck carried by said second yoke, a rotatable finishing tool positioned to engage the surface of a piece of work carried by the chuck at the intersection of said yokes, and means to oscillate the first and second yokes about the specified axis.

3. A work holding fixture comprising a yoke having vertically extending arms, spaced arms pivotally connected to the vertically extending arms of the yoke, a chuck carried by the spaced arms to position a piece of work at the intersection of the spaced arms with arms of the yoke, a finishing tool positioned to engage the work,

15 gear means to oscillate the yoke about a vertical axis, gear means to oscillate the spaced arms about the intersection of the arms of the yoke, and means to rotate the finishing tool relative to the work.

20 4. A work holding fixture comprising a base, a yoke journaled in the base and having vertically extending arms, a work carrying yoke having spaced arms pivotally connected to the vertically extending arms of the first mentioned yoke, a chuck in the work carrying yoke to position a piece of work at the intersection of said arms, a rotatable member carrying the chuck, a rotatable finishing tool positioned to engage the surface of the work in the chuck, worm and worm gear

25 means to oscillate the first mentioned yoke about a vertical axis and to rotate the work carrying yoke about a horizontal axis and flexible means to drive the worm and worm gear means to rotate the work against the rotating finishing tool and

30 35 to simultaneously oscillate the work about vertical and horizontal axes intersecting at the center of the work.

5. A work holding fixture comprising two yokes each having spaced arms, pivotal connecting means between said arms, a work holder carried by one of the yokes to position a piece of work at the intersection of the yokes, a finishing tool positioned to engage the work, means to rotate the work holder, and means to oscillate said yokes about vertical and horizontal axes.

6. A work holding fixture comprising a yoke having a vertically extending arm, an arm pivotally connected to the vertically extending arm of the yoke, a chuck carried by the second mentioned arm to position a piece of work at the intersection of said arms, a finishing tool positioned to engage the work, means to oscillate the yoke about a vertical axis, means to oscillate the second mentioned arm about the intersection of the arm of the yoke, means to rotate the finishing tool, and one-way driving means to rotate the work relative to the finishing tool.

7. A work holding fixture comprising a base, a vertically extending arm journaled in the base, 60 a work carrying arm pivotally connected to the vertically extending arm, a chuck in the work carrying arm to position a piece of work at the intersection of said arms, a rotatable member carrying the chuck, a rotatable finishing tool positioned to engage the surface of the work in the chuck, and means to oscillate said arms and to rotate the chuck carrying rotatable member to rotate the work against the rotating finishing tool and to simultaneously oscillate the work about axes intersecting at the center of the work.
